Primary Examiner — Joseph Kukella*(74) Attorney, Agent, or Firm* — Wood Herron & Evans LLP**CLAIM**

The ornamental design for a timer, as shown and described.

DESCRIPTION

FIG. 1 is an isometric view of one embodiment of timer illustrating our new design.

FIG. 2 is a front view thereof.

FIG. 3 is a rear view thereof.

FIG. 4 is a right side view thereof.

FIG. 5 is a left side view thereof.

FIG. 6 is a top view thereof.

FIG. 7 is a bottom view thereof.

FIG. 8 is an isometric view of our design of FIGS. 1-7 in combination with a display card.

FIG. 9 is a front view thereof.

FIG. 10 is a rear view thereof.

FIG. 11 is a right side view thereof.

FIG. 12 is a left side view thereof.

FIG. 13 is a top view thereof; and,

FIG. 14 is a bottom view thereof.

Any elements shown in broken lines form no part of the claimed invention, and are instead included to show environmental aspects of the claimed invention.
